[57] CLAIM

The ornamental design for a utility pole, as shown and described.

DESCRIPTION

FIG. 1 is a front perspective view of the utility pole showing my new design;

FIG. 2 is a fragmentary front elevational view thereof on an enlarged scale, the pole being broken away for convenience of illustration;

FIG. 3 is a top plan view thereof on an enlarged scale; and,

FIG. 4 is a bottom plan view thereof on an enlarged scale.
